DRESSER OR THE LIKE

Huey T. Keller, 1609 Davidson Road,
High Point, N.C. 27260

Filed Mar. 8, 1972, Ser. No. 233,012

Term of patent 14 years

Int. Cl. D6—04

U.S. Cl. D6—164

FIG. 1 is a front elevational view of a dresser or the like showing my new design, the opposite side being substantially plain and unornamented;

FIG. 2 is a side elevational view of such design, the opposite side being substantially a mirror image thereof;

FIG. 3 is a top plan view of such dresser.

I claim:

The ornamental design for a dresser or the like, as shown.
